UNITED STATES PATENT OFFICE.

FRANK E. CASE, OF CANTON, OHIO.

DENTAL CHAIR.

No. 799,972.

Specification of Letters Patent.

Patented Sept. 19, 1905.

Application filed August 7, 1903. Serial No. 168,555.

To all whom it may concern:

Be it known that I, FRANK E. CASE, a citizen of the United States, residing at Canton, in the county of Stark and State of Ohio, have invented certain new and useful Improvements in Dental Chairs, of which the following is a specification.

The invention relates to a pump for elevating and lowering the vertically-extensible parts of a chair-base; and the objects of the improvements are to provide a release-valve in the pump by which the rate of descent can be regulated and controlled, together with readily-detachable means for operating the pump-plunger and the release-valve. These objects are attained by the arrangement, construction, and mechanism illustrated in the accompanying drawings, in which—

Figure 1 is a perspective vertical section of the chair-base, showing the pump in place; Fig. 2, a vertical section of the pump in the longitudinal middle line, showing the outline of the base in broken lines; Fig. 3, a perspective view of the pump, showing some of its parts detached and opposite their proper places.

Similar numerals refer to similar parts throughout the drawings.

The floor-plate 1 is preferably circular in form, and on its upper side is provided the annular flange 2. The base 5 is preferably formed as a cylinder, with its sides somewhat flattened, and is open above, below, and in front. The base terminates below in the external angular flange 6, which is continued across the opening in front to complete the circle, and this flange rests and rotates on the floor-plate flange. The box-standard 9 is formed similar in section to the base and telescopes therein, being provided with the usual vertical grooves for the corresponding tongues formed in the base, and the body-standard 12 is likewise formed and telescopes in the box-standard, being provided with the similar grooves for the corresponding tongues in the box-standard. The body of the chair (not shown) is mounted on the body-standard and is raised and lowered by the elevation and depression of the respective standards.

The pump-block 15 is supported in the base by the lugs 16, formed near the forward edges on its sides and near the top, the inclined lower edges 17 of which lugs hooking over the bosses which are formed near the top on the forward edges of the base, and it is held in position on these supports by the

stay-pin located on the forward part of the base-flange, which pin enters the corresponding recesses 20 in the under side of the bottom. The oil-reservoir 32 is formed in the upper part of the pump-block, and the plunger-cylinder 33 is preferably located in the forward part of the reservoir and is screwed into the socket 34, which is provided for it in the thick bottom 35 of the pump, the washer 36 being provided on the lower end of the cylinder to pack against the bottom of the socket and make a tight joint.

The release-tube 37 is preferably located in the rear part of the reservoir and is screwed into the socket 38, which is provided for it in the bottom of the block, the shoulders 37^a being preferably provided on the tube to make a tight fit against the bottom of the reservoir, and the piston-cylinder 39 is preferably located on the rear side of the block and is screwed into the socket 40, which is provided for it in the rear extension 41 of the bottom of the block, and the upper end of the cylinder is held in the collar 42, which is formed on the upper rear side of the block. The main port 43 is located in the bottom of the block and extends from the piston-cylinder socket directly forward to a point under the plunger-cylinder socket, with which it communicates through the aperture 44 in the bottom of this socket, and the release-port 45 communicates from the main port to the bottom of the release-tube socket.

The check-valve 46 is formed in the lower end of the plunger-cylinder and preferably comprises a ball-valve resting in a cup and normally held up against its seat by a coil-spring, which spring is sustained by the inner rim of the packing-washer 36. The main valve 47 is formed in the lower end of the plunger 48 and preferably comprises a ball-valve resting in a cup and normally held up against its seat by a coil-spring, which spring is sustained by the bushing 48^a, which is screwed into the lower end of the plunger. The plunger is reduced in diameter above the main valve, thereby forming the annular port 49, into which port the oil enters from the reservoir through the apertures 50 in the plunger-cylinder located near the bottom of the reservoir. The screen-box 51 is preferably provided around these apertures to keep out dirt or grit. The valve-ports 52 communicate between the annular port and the main valve. The bell-flange 53 is formed on the upper end of the plunger and operates in and neatly fills the aperture 54,

which is provided for it in the top of the pump. The rim of the bell-flange is adapted to telescope outside of the plunger-cylinder, and the plunger is normally held up by the 5 coil-spring 55, which is located around the cylinder between the screen-box and the bell-flange.

The plunger is depressed by means of the lifting-lever 56, which extends, preferably, on 10 the right side of the chair to the rear from the end of the pump-shaft 57, which shaft is transversely journaled in the forward side of the block. The arms 58 and 58^a extend rearward from this shaft on each side of the block, 15 and these arms are pivotally connected by the links 59 to the sides of the yoke 60, which arches over the upper end of the plunger. An adjustable contact between the yoke and the plunger is provided by the screw 61 in the 20 yoke, the lower end of which screw is adapted to enter the cup-recess 62 in the upper end of the plunger.

The release-valve 63 is formed in the upper end of the release-tube, and the valve proper 25 preferably comprises a ball-valve resting in a cup and normally held up against its seat in the end of the exit-port by a coil-spring, which spring is sustained on the internal annular shoulder 64, formed in the release-tube. To 30 limit and regulate the flow of oil through the axial exit-port 65 from the release-valve, I provide in this port the regulating-pin 66, which pin abuts against the ball-valve and is constricted in diameter in the middle, to which 35 part it is tapered from each end. The bell 67 rests on the upper end of the regulating-pin and its flanges extend down freely around the release-valve and operate in and loosely fill the aperture 68, provided for it in the top of the 40 pump. Such oil as may escape and overflow from the piston-cylinder through the notch 69 finds its way into the reservoir through the aperture 68.

The release-valve is operated by means of 45 the releasing-lever 70, which extends rearward, preferably on the right side of the chair from the sleeve 71, which is journaled on the release-shaft 26, transversely mounted in the forward part of the block. The release-arm 50 72 extends rearward from this sleeve along the side of the pump, and this arm is pivotally connected by the link 73 with the rear end of the idle lever 74, which is pivoted between the ears 75 on the top of the pump. The idle lever 55 and its companion arm 74^a are curved over the trunnions 76, which project from the sides of the release-valve bell, and by depressing the releasing-lever, and thereby the idle lever, the bell is carried downward, which pushes the 60 regulating-pin and the ball-valve down and opens the exit-port. This movement is limited by the adjustable stop-screw 77, which screw is located in the companion arm and strikes against the upper edge of the adjacent 65 pump-ear.

The opening of the exit-port from the release-valve is increased as the regulating-pin is depressed, by reason of the reduced diameter of the pin, so that the amount of flow of oil from the release-valve can be regulated at 70 will by varying the depression of the releasing-lever, which is manipulated by the operator's foot on the pedal 78. The transverse ports 79 are provided in the release-valve and lead directly from about the middle of the 75 exit-port adjacent to the reduced part of the regulating-pin to the sides of the valve, so as to afford a ready exit for the oil after it has entered the exit-port around the enlarged lower end of the regulating-pin. The ends 80 of the regulating-pin are made only slightly less in diameter than the exit-port, and I prefer to make one end of a little less diameter than the other, so that the initial amount of flow of oil from the release-valve can be varied 85 by inverting the pin end for end. It will be understood that the regulating-pin can be made single instead of double, as illustrated and described, without affecting the nature of the invention—that is, it can be tapered from 90 the enlarged lower end to a reduced upper end; but I prefer to use the double pin because it gives a greater amount of variation by turning it end for end.

The piston-rod 80 operates in the piston-cylinder and is provided with the usual head 81. The upper end of the piston-rod is attached to the box-standard by means of the bracket 82, extending through and operating in the slot 83, provided for it in the body-standard. When the box-standard is elevated, motion is conveyed to the body-standard by means of the usual pulleys, as 84, pivoted on each inner side near the top of the box-standard, and the chains 85, passing over 100 the pulleys and attached to the base 5 and to the body-standard, as at 89.

The means for joining and manipulating the rotatable base on the floor-plate and for entering and supporting the pump in the base, 110 which are illustrated and partly described, but not claimed, herein, are made the subject-matter of a divisional application filed March 28, 1904, Serial No. 200,247.

What I claim as my invention, and desire to 115 secure by Letters Patent, is—

1. In a chair-pump, a block having a reservoir therein and an aperture in the top, a cylinder in the reservoir, a spring-sustained plunger adapted to operate in the cylinder and having a bell-flange on its upper end adapted to operate in the aperture and around the cylinder, a yoke having a bearing on the plunger, a rock-shaft mounted on the block and having lateral arms, and connections between the 120 yoke and the arms.

2. In a chair-pump, a block having a release-tube therein, a spring-closed valve in the tube, an endwise-movable pin protruding from the tube and abutting on the valve, a bell resting 125

on the pin and freely telescoping over the tube, trunnions on the bell, levers pivoted on the block and curving over the trunnions, and means for depressing the levers.

- 5 3. In a chair-pump, a release-tube having an axial exit-port with a diverging transverse port therein, a spring-sustained valve adapted to close the inner end of the axial port, an end-wise-movable pin in the axial port abutting on the valve, the pin being tapered from ends slightly smaller than the axial port to a constricted middle part adjacent to the transverse port; and means for actuating the pin.
- 10 4. In a chair-pump, a release-tube having an

exit-port therein, a spring-sustained valve 15 adapted to close the inner end of the port, an endwise-movable tapered pin in the port having its enlarged end slightly smaller than the port and abutting against the valve, with means for free exit adjacent to the small end of the 20 pin and means for actuating the pin.

In testimony whereof I have signed my name to this specification in the presence of two subscribing witnesses.

FRANK E. CASE.
